UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER-SUPPORTING MECHANISM FOR SEWING-MACHINES.

1,375,531.

Specification of Letters Patent. Patented Apr. 19, 1921.

Application filed July 17, 1917. Serial No. 181,092.

To all whom it may concern:

Be it known that I, JAMES R. MOFFATT, a citizen of the United States, residing at Chicago, in the county of Cook, State of Illinois, have invented certain new and useful Improvements in Looper-Supporting Mechanism for Sewing-Machines, of which the following is a description, reference being had to the accompanying drawing and to the figures of reference marked thereon.

The invention relates to new and useful improvements in looper-supporting mechanisms for sewing machines, and more particularly to a looper support on which two 15 loopers are mounted which are adapted to cooperate respectively with needles.

An object of the invention is to provide means whereby the loopers may be adjusted toward and from the needles and relative to 20 each other, without disturbing their angular position relative to a horizontal line, whereby said loopers will maintain uniform drags on their respective needle thread loops during the loop-shedding movement of said 25 loopers, and also permit the simultaneous shedding of said loops.

In the drawings,—

Figure 1 is a front view of a sewing machine having my improvement applied thereto, the work support being broken away to 30 show the looper-carrier and the looper support therefor;

Fig. 2 is an enlarged front view of the looper-carrier;

Fig. 3 is a rear view of the same;

Fig. 4 is a perspective view of the looper from the rear, showing the parts separated;

Fig. 5 is a diagrammatic view, showing the manner of adjusting the loopers; and

Fig. 6 is a view similar to Fig. 3, but showing a slightly modified form of the invention.

The invention is directed particularly to a two-needle machine having a looper coöperating with each needle and wherein the loopers are mounted so as to move in planes at right angles to the line of feed. The two loopers are mounted on the same looper-carrier and this looper-carrier is oscillated and moved sidewise for giving the loopers their proper movements.

It has been customary to form the link for oscillating the looper-carrier, so that the carrier may be shifted for properly setting the 55 loopers relative to the needles. The loopers

should simultaneously cross their respective needles when entering the needle thread loops just above the eyes in the needles and by adjusting the link this timing of at least one looper may be accomplished. It sometimes occurs that when one looper is properly adjusted to coöperate with its needle, the other looper is out of timing, and the present invention is directed particularly to a means for mounting one of the loopers on 60 the looper-carrier, so that it may be adjusted bodily for bringing out a proper timing or setting thereof relative to its needle after the other loop has been properly set by adjusting said link.

Furthermore, it is essential that both needle loops shall be dropped or released simultaneously by the loopers, so that a single thread-controlling means may be used for both needle threads. The adjustment of the 75 loopers above referred to will accomplish this result, provided the drag of the loopers on their respective needle thread loops has not been changed. The adjusting means is, therefore, so constructed that the looper may 80 be shifted bodily without disturbing or changing its drag on its needle loop.

Referring more in detail to the drawings, I have shown my improved looper supporting mechanism as applied to a sewing machine having a bed plate 1, an overhanging arm 2, in which a needle bar 3 reciprocates. This needle bar carries two needles 4 and 5. These needles 4 and 5 are set in a line diagonal to the line of feed. Coöperating with 85 the needle 4 is a looper 7 and coöperating with the needle 5 is a looper 6.

These loopers are mounted on a looper carrier 8 which is pivoted at 9 to a looper support or rocker 10. The looper carrier is 90 oscillated by means of a link 11 which is connected to the ball stud 12 on the looper carrier. The other end of this link is connected at 13 to the needle lever extension 14 of the needle lever 15. This needle lever is 95 oscillated by an eccentric strap 16, coöperating with an eccentric 17 on the main shaft.

The link 11 is provided with threads 18 at the opposite ends and these threads are right and left hand threads so that the turning of 100 the link will either shorten the link or lengthen the same. Adjustably mounted on the main looper carrier 8 is an auxiliary looper carrier 19. The main looper carrier 105 is formed with a rib 20 while the auxiliary 110

carrier is formed with a groove 21. Said auxiliary carrier has an elongated slot 22 which is adapted to receive a screw 23 which holds the auxiliary carrier on the main carrier but permits the same to be adjusted relative thereto. The rib and groove are arranged in a line at right angles to the longitudinal center of the main part of the carrier.

10 The main looper carrier 8 has a socket for the looper 7 and said looper is held in the socket by means of a set screw 24. The auxiliary looper carrier has a transverse socket 25 formed therein. A sleeve 26 has a laterally extending stud 27 which is adapted to be received by said socket 25 and a set screw 28 serves to lock the stud in place. Said stud has a flat side which serves to hold the sleeve in a position with its longitudinal axis substantially parallel with the longitudinal axis or center of the main looper carrier.

15 The looper 6 has a shank which is mounted in this sleeve and a set screw 29 serves to hold the shank in place in the sleeve. By loosening this screw 29 the looper 6 may be adjusted vertically in the sleeve. By loosening the screw 28 the sleeve may be shifted sidewise and this enables the looper carrier 30 thereby to be moved sidewise relative to the other looper. By loosening the screw 23 the auxiliary carrier may be shifted, as above described.

20 In Fig. 5 of the drawings, I have shown diagrammatically the needles 4 and 5 and the loopers 6 and 7. Let us assume that the link 11 has been adjusted so as to shift the carrier to properly position the looper 7 so that the point of this looper will cross the needle just above the eye of the needle as it enters the needle loop. Let us assume also that owing to a faulty construction of the looper, when the looper 6 is properly timed as above noted, that the looper 7 is slightly 25 out of timing. That is, its point is back from the needle 4, as shown in this figure of the drawings. The pivotal center of the looper carrier, that is the axis about which the looper carrier turns, is indicated at 9^a in said figure. The outer curved surface of the looper is concentric with this pivot point of the carrier and is indicated by the full circular line a—a. The under surface of the looper, as is well known, is curved about a point slightly to the right of the center 30 9^a, so that its curved surface is eccentric to the pivot point of the looper-carrier. The purpose of this eccentric surface is to produce a drag on the needle thread loop to insure the opening of the thread triangle for the needle on its next descent. The angular position of this eccentric surface to a horizontal line also determines the time of dropping or shedding of the needle loop.

35 60 65 66 In the drawings I have indicated the

chord of the outer curved surface of the looper 6 by the line b. By loosening the screw which holds the auxiliary carrier, said auxiliary carrier may be shifted bodily in a line parallel with the line x—x, which is at 70 right angles to the longitudinal line or axis y—y of the main looper-carrier. This shifts the chord b to the position indicated by the broken line c. While the looper point has been brought up to the needle it is slightly 75 above the position where it should be when it crosses the needle to enter the needle loop, and, therefore, the looper is then bodily adjusted vertically to bring the chord of its outer curved surface to the line d. It will be 80 noted that the chords c, b and d are all parallel, and, therefore, the looper 6 has been adjusted and properly set without disturbing the position of the eccentric surface.

85 By thus maintaining the curved surface of the looper 6 always in the same position relative to the looper 7, I am able to adjust the looper, and when the loopers are in their several adjusted positions, they will simultaneously drop the needle loops. It will be 90 readily understood that if the looper 6 be shifted about the pivot point for adjustment, then the under curved surface will be varied or shifted from its original position and will either hang onto the needle loop 95 longer or release it a little quicker. It is essential that both the needle loops should be dropped simultaneously, as in this type of machine it is desirable to use a single thread controlling mechanism for both 100 threads. The adjustments described enable the loopers to be brought into proper timing and both loopers will also shed their needle loops at exactly the same time.

105 The auxiliary carrier is shown as provided with a large opening for the screw 29. This permits the auxiliary carrier to be adjusted and at the same time the set screw is readily accessible.

110 In the modification shown in Fig. 6, the loopers 6 and 7 are carried by the main looper carrier 8 and the looper 6 is mounted in an auxiliary carrier 19 which is adjustably mounted on the main looper carrier and held in adjusted position by means of a 115 screw 19^a. A looper 6 is formed with a vertically disposed shank adapted to enter a socket formed directly in the auxiliary carrier and said looper is held in said socket by means of a screw 19^b. The auxiliary 120 carrier is provided with a laterally extending lug 30 and a stop screw 31 extends up through this lug. The purpose of the stop screw is to fix the vertical position of the looper 6 so that it may be readily removed and replaced and when replaced it can be brought back to the same set position against the stop. The auxiliary carrier is held from movement about the screw 19^a by a ledge 125 32 on which it rests.

From the above description it will be apparent that the looper 6 may be adjusted in a direction substantially at right angles to the longitudinal axis of the looper carrier 5 by shifting of the auxiliary carrier on the main carrier and that the looper may be adjusted bodily vertically by releasing the screw 19^b and shifting the stop screw 31. Through these two adjustments the looper 10 may be timed in the manner above described.

Having thus described my invention, what I claim as new and desire to secure by Letters Patent is:—

1. The combination with a pair of needles, of a looper coöperating with each needle, a looper-carrier for both loopers, and means whereby one of said loopers may be adjusted relative to the other of the looper-carrier and in a direction substantially at 15 right angles to the longitudinal axis of the looper-carrier without disturbing its position relative to a horizontal line at the time of shedding its needle-thread loops.

2. The combination with a pair of needles, of a looper for each needle, a looper-carrier on which said loopers are mounted, one of said loopers being mounted directly on said carrier, and an auxiliary carrier for the second looper, means for adjustably securing said auxiliary carrier to the main looper-carrier, whereby said auxiliary carrier may be shifted bodily in a direction substantially at right angles to the longitudinal axis of the looper-carrier and without disturbing its position relative to a 30 horizontal line.

3. The combination with a pair of needles, of a looper for each needle, a looper-carrier on which said loopers are mounted, one of said loopers being mounted directly 40 on said carrier, and an auxiliary carrier for the second looper, means for adjustably securing said auxiliary carrier solely to the main looper-carrier, whereby said auxiliary carrier may be shifted bodily in a direction 45 substantially at right angles to the longitudinal axis of the looper-carrier and without disturbing its position relative to a horizontal line, and means whereby said 50 second looper may be adjusted toward and from the center of the looper-carrier.

4. The combination with a pair of needles, of a pivoted looper carrier, means for swinging said looper carrier about its pivot, 55 including devices whereby the oscillating position of the looper carrier may be shifted, a looper for each needle mounted on said carrier, one of said loopers being mounted directly on the carrier and an auxiliary looper carrier for the other looper, means whereby said auxiliary looper carrier 60 may be shifted bodily in a direction substantially at right angles to the longitudinal axis of the carrier and without dis-

turbing its position relative to a horizontal 65 line, and means whereby the looper may be adjusted toward and from the center of the looper carrier on said auxiliary carrier.

5. The combination with a looper carrier having a socket for a looper, means for holding the looper in the socket, an auxiliary carrier adjustable vertically at right angles to the longitudinal axis of the main looper carrier, a sleeve mounted on the auxiliary looper carrier and having a socket 75 for a second looper, means for adjustably holding said sleeve on the looper carrier whereby it may be shifted for adjusting one looper bodily laterally toward and from the other.

6. The combination with a looper carrier adapted to be bodily supported, said looper carrier having a socket for the looper, a looper mounted therein and means for holding the looper in said socket, an auxiliary 85 looper carrier mounted on the main looper carrier, said auxiliary looper carrier and main carrier having a rib and groove connection disposed so as to permit the auxiliary carrier to be adjusted in a direction 90 substantially at right angles to the longitudinal axis of the main carrier, a second looper mounted on said auxiliary carrier.

7. The combination with a looper carrier adapted to be bodily supported, said looper carrier having a socket for the looper, a looper mounted therein and means for holding the looper in said socket, an auxiliary 95 looper carrier mounted in the main looper carrier, said auxiliary looper carrier and main carrier having a rib and groove connection disposed so as to permit the auxiliary carrier to be adjusted in a direction substantially at right angles to the longitudinal axis of the main carrier, a second 100 looper mounted on said auxiliary carrier, said auxiliary carrier having a transverse socket, a sleeve having a projecting stud mounted in said socket, means for holding the stud in said socket whereby it may be 105 adjusted in a direction at right angles to the plane of movement of the looper carrier, said sleeve having a socket for said second looper and means for adjustably supporting said looper in said socket.

8. The combination with a looper carried adapted to be bodily supported, said looper carrier having a socket for the looper, a looper mounted therein and means for holding the looper in said socket, an auxiliary 120 looper carrier in the main looper carrier, said auxiliary looper carrier and main carrier having a rib and groove connection disposed so as to permit the auxiliary carrier to be adjusted in a direction substantially at right angles to the longitudinal axis of the main carrier, a second looper mounted on said auxiliary carrier, said

auxiliary carrier having a transverse socket, a sleeve having a projecting stud mounted in said socket, means for holding the stud in said socket whereby it may be adjusted 5 in a direction at right angles to the plane of movement of the looper carrier, said sleeve having a socket for said second looper and means for adjustably supporting said looper

in said socket and an adjustable stop for positioning the looper in the sleeve. 10

In testimony whereof I affix my signature in the presence of two witnesses.
